C. H. BURK.
SHOE FOR SAD IRONS.
APPLICATION FILED OCT. 23, 1909.

969,335.

Patented Sept. 6, 1910.

UNITED STATES PATENT OFFICE.

CHARLES H. BURK, OF CHICAGO, ILLINOIS,

SHOE FOR SAD-IRONS.

969,335.

Specification of Letters Patent.

Patented Sept. 6, 1910.

Application filed October 23, 1909. Serial No. 524,265.

To all whom it may concern:

Be it known that I, CHARLES H. BURK, citizen of the United States, residing at Chicago, in the county of Cook and State of Illinois, have invented certain new and useful Improvements in Shoes for Sad-Irons; and I do hereby declare the following to be a full, clear, and exact description of the invention, such as will enable others skilled 5 in the art to which it appertains to make and use the same.

This invention relates to a novel construction in a shoe for sad-irons, the object being to provide a device of this character which is adapted to be kept always on the ironing board and receive successive hot irons of either the double or single pointed varieties, and consists in the features of construction and combinations of parts hereinafter fully described and claimed.

In the accompanying drawings illustrating this invention: Figure —1— is a perspective view of a shoe constructed in accordance with my invention. Fig. —2— is a top plan view of the same. Fig. —3— is a side elevation of the same. Figs. 4 and 5 are fragmentary detail horizontal sections on the lines 4—4 and 5—5 respectively, of Fig. 3 showing the shape in cross-section 30 of the end posts of the device.

My present invention has for its object to provide a shoe for sad-irons made of a single piece of relatively thin sheet metal of such shape as to enable it to receive either 35 the ordinary flat heel type or the double pointed or canoe shape sad-irons, said shoe serving to provide an ironing surface which is always clean and smooth, and which is further equipped with means for securing 40 the sad-iron therein so constructed as to insure the requisite strength and durability.

My said shoe comprises the body portion A having parallel side edges B converging at one end and meeting in a point C, the 45 said body portion terminating at its other end in a straight edge D disposed at right angles to the side edges B and provided midway between the latter with a V-shaped extension E. The said body portion is 50 equipped with an integral edge flange F completely surrounding the same and which

at the point C and the free end of the extension E is extended upwardly to form end posts G and H respectively which are of greater width at their bases than at their 55 free end portions, the said posts being V-shaped in plan section except at their extreme free ends. The extreme free end of the post H is flat and is equipped with side projections forming inverted hooks I which 60 are adapted to receive and engage the free ends of springs J coiled between their ends as at K and pivotally secured at their other ends to the free end of the post G, the said coils K bearing upon the upper face of the 65 contained sad-iron and serving to support the shoe thereon in such manner as to maintain the body portion thereof in close contact with the lower face of the said sad-iron. The V-shaped form of the posts renders the 70 latter relatively stiff and prevents them from being easily bent or distorted.

I claim as my invention:

1. A shoe for sad-irons, comprising a plane body-portion having parallel side 75 edges converging at one end and meeting in a point, the rear edge of said body-portion being disposed transversely to said side edges, said body-portion being equipped with a substantially V-shaped extension 80 midway between the ends of said rear edge, an edge flange integral with said body-portion completely surrounding the latter, said edge flange being equipped with vertical extensions at the extreme ends of said 85 body-portion, said extensions constituting standards, and yielding supporting means disposed in engaging relation to said standards and the contained sad-iron to support 90 said shoe on the latter.

2. A shoe for sad-irons, comprising a plane body-portion having parallel side edges converging at one end and meeting in a point, the rear edge of said body-portion being disposed transversely to said side 95 edges, said body-portion being equipped with a substantially V-shaped extension midway between the ends of said rear edge, an edge flange integral with said body-portion completely surrounding the latter, said edge 100 flange being equipped with vertical extensions at the extreme ends of said body-portion.

tion, said extensions constituting standards, and being V-shaped in plan section, and yielding supporting means disposed in engaging relation to said standards and the 5 contained sad-iron to support said shoe on the latter.

In testimony whereof I have signed my

name in the presence of two subscribing witnesses.

CHARLES H. BURK.

Witnesses:

RUDOLPH Wm. LOTZ,
M. M. BOYLE.
